UNITED STATES PATENT OFFICE.

HERMAN ABRAMS, OF PHILADELPHIA, PENNSYLVANIA, ASSIGNOR TO CRESCENT
BRASS MFG. CO., OF READING, PENNSYLVANIA, A CORPORATION OF PENNSYLVANIA.

DESIGN FOR A PLATE FOR LIGHTING FIXTURES.

Application filed December 29, 1927. Serial No. 24,692. Term of patent 7 years.

To all whom it may concern:

Be it known that I, HERMAN ABRAMS, a citizen of the United States, residing at Philadelphia, in the county of Philadelphia and State of Pennsylvania, have invented a new, original, and ornamental Design for a Plate for Lighting Fixtures of which the following is a specification, reference being had to the accompanying drawing, forming part hereof, in which—

Fig. 1 is a side elevation; and Fig. 2 is a bottom plan view showing my new design, only a part thereof being shown in full lines, it being understood that the design is repeated throughout the entire surface.

I claim:

The ornamental design for a plate for lighting fixtures, as shown.

HERMAN ABRAMS.
